SWITCH STAND

Application filed May 10, 1930. Serial No. 451,232.

The invention relates to switch stands which are used for operating railroad switches.

According to a preferred form of the invention, a switch stand is provided by which the switch points may be manually operated from one position to the other and locked in either position. Spring assemblies may be provided for allowing a train trailing the switch to displace the switch from either set position, if the switch is set against the train. If desired, a buffer or dash pot arrangement may be provided for preventing the quick return of the switch points to their set position when moved by a train until the last wheel has passed over the switch. A visual signal may be provided to indicate the true position of the switch points at all times. The actuating mechanism for operating the switch points, the spring return mechanism and the buffer mechanism may be all located in the same housing.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation with parts in section of the switch stand;

Fig. 2 is a section on the line 2—2 of Fig. 1; and

Fig. 3 is a section on the line 3—3 of Fig. 2.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical com-

mercial embodiment of the invention is shown, but as such illustration is primarily for purposes of disclosure, it will be understood that the structure may be modified in various respects without departure from the broad spirit and scope of the invention as hereinafter defined and claimed.

Referring now to the drawings, the switch stand is shown suitably bolted or spiked to the cross-ties 10. The switch stand comprises a housing 11 which is separable into a lower section 12 and upper sections 13, 14 and 15.

Secured within the lower section 12 is a pair of spring assemblies 16 and 17. Since these spring assemblies are identical in construction and in mounting, a description of the spring assembly 17 only will be given.

The spring assembly 17 comprises a bolt 18 passing through the wall of the section 12 and a lug 19 projecting from the bottom of the section. Disposed upon the bolt 18 is a pair of sleeves 20 and 21 between which is positioned a coil spring 22 surrounding the bolt 18.

Surrounding the sleeves 20 and 21 and spring 22 is a third sleeve 23 having a flange 24 at one end which engages a flange 25 on the sleeve 20. A removable flange 26 is threaded onto the sleeve 23 at its other end for engagement with the flange 27 on the sleeve 21. A lug or abutment 28 is secured to the sleeve 23 as shown.

Journalized in the upper section 14 is a star block 29 having four rollers 30, 31, 32 and 33 journaled between suitable lugs and positioned at the corners of a rectangle. It will be seen that the lug 28 is normally positioned between rollers 32 and 33 while the lug 34 on the other spring assembly 16 is normally positioned between the rollers 30 and 31.

For suitably controlling the movement of the star block 29 a dash pot or buffer mechanism 35 is provided. The buffer 35 comprises a cylinder 36 within which is positioned a piston 37 having a piston rod 38 connected to the star block 29 by a pivot 39. The cylinder 36 is connected to the wall of section 12 by a pivot 40.

100

The details of construction of the buffer 35 are well known and in themselves form no part of the present invention, except in combination with the rest of the apparatus. 5 Briefly, the cylinder 36 is provided with a groove 41 extending for part of its length. A bypass passage 42 is provided for connecting the ends of the cylinder. A sleeve valve 143 in passage 42 retards passage of the 10 retarding fluid through the passage. A one-way valve 43 is also provided for preventing any flow of the retarding fluid through it in one direction and for allowing a free flow of retarding fluid through it in the other direction. 15

The star block 29 has a square seat 44 in which is seated a square end 45 on the locking block or sliding sleeve 46. Within the sleeve 46 which has a square opening is a square or 20 inner sleeve 47. Within the squared or inner sleeve is a square spindle 48 which has circular bearings at 49 and at 50 on the star block 29 and at 51 on the bottom of the casing section 12. Secured to the upper end of the 25 spindle 48 is a suitable signal 52 and at the lower end of the spindle 48 is secured a crank arm 53 to which is pivoted a connecting rod 54 which extends to the switch points, as is well known in the art.

30 A handle 55 is provided which is pivoted to a lug 56 on the square sleeve 47. A pair of lugs 57 is provided on each side of the sliding sleeve 46 between which are disposed the bifurcated arms 58 of the handle 55. A lug 35 59 is provided on the sliding sleeve 46 for seating within a slot 60 in the handle 55. A hole 61 may be provided in the lug 59 for the reception of a particular lug or other locking device (not shown) to lock the switch 40 points in set position, as is well known in the art.

In operation, with the parts in the position shown in Fig. 1, the switch points are 45 in one set position. When it is desired to operate the switch points to the other set position the locking device cooperating with the hole 61 is removed and the handle 55 is raised to disengage the squared end 45 from its seat 44, and then the concentric members 50 46, 47 and 48 are rotated 90° in which position the squared end 45 is reseated in the seat 44. The handle 55 may be locked in this position.

55 It will be noted that when the switch points are operated as above described the star block 29 remains stationary, the crank arm 53 on the end of spindle 48 alone turning to operate the switch points.

If, however, the switch points are set 60 against a train and the train trails the switch points with them set against it, the wheels will force the switch points from their set position operating the crank arm 53 and turning the entire assembly of concentric members 46, 47 and 48 together with the star

block 29. The rotation of the star block 29 causes the lug 28 on one spring assembly 17 to move in one direction and the lug 34 on the other spring assembly 16 to move in the other direction compressing the springs 70 therein. The rotation of the star block 29 will also operate the buffer 35. It will be seen that the piston 37 will be moved to the right by the wheels of the train and that no substantial impediment will be offered by the buffer at the first part of its movement 75 due to the groove 41 nor at the last part of its movement due to the one-way valve 43, allowing the bypass of the retarding fluid. To prevent springs of the spring assemblies 16 and 17 from returning the switch points to set position between passage of the wheels of the train, the sleeve valve 143 retards the back flow of retarding fluid, the buffer 35 thus preventing the quick return of the 80 switch points between the passage of the successive wheels of the train. 85

After the train has passed, however, the displacing force of the wheels being removed, the springs of the spring assemblies 16 and 17 slowly force the switch points to their set 90 position. The movement of the piston 37 may be comparatively slow until they have almost reached their set position, at which point the movement of the piston may be accelerated 95 due to the action of the groove 41. It will be understood that this action of the buffer and of the springs will take place in either set position of the switch points.

Thus a switch stand has been described 100 which is compact, having all of the operating parts enclosed within a housing where they are protected from dirt and from injury. The switch stand is rigid and permits free operation of the switch points from one position to the other. The points must be fully thrown before the switch stand can be latched, and the target or signal always indicates the position of the switch points. The spring mechanisms, for accomplishing the automatic 105 return, are located within the housing and are independently connected with the switch stand spindle through roller bearings and either of the spring assemblies will automatically return the trailed switch points to original set position when set against train movement. The buffer is also located within the housing and allows free opening of the points by the train but retards their return to set position so that the points will remain open 110 until the last pair of wheels has passed. At this point the points may be returned to set position as slowly as desired until almost completely returned, when the points may be closed rapidly to set position. 115

While certain novel features of the invention have been shown and described and are pointed out in the annexed claims, it will be understood that various omissions, substitutions and changes in the forms and details 120 125 130

of the device illustrated and in its operation may be made by those skilled in the art without departing from the spirit of the invention.

What is claimed is:

5. 1. In a switch stand, a switch stand casing, means in said casing for operating the switch points to either set position, independent yieldable devices in said casing for permitting the switch points to be displaced from set position by a train, in either set position of the points, and means in said casing for holding said points in displaced position between the passage of successive wheels of the train but allowing either or both of said yieldable devices to return the switch points to set position after the train has passed, and a signal supported on said casing indicating the position of the switch points at all times.
10. 2. In a switch stand, a switch stand casing, means in said casing for operating the switch points to either set position, yieldable devices in said casing for permitting the switch points to be displaced from set position by a train, and means in said casing for holding said points in displaced position between the passage of successive wheels of the train but allowing said devices to return the switch points to set position after the train has passed.
15. 3. In a switch stand, a switch stand casing, means in said casing for operating the switch points to either set position, independent yieldable devices in said casing for permitting the switch points to be displaced from set position by a train, in either set position of the points, and means in said casing for holding said points in displaced position between the passage of successive wheels of the train but allowing either or both of said devices to return the switch points to set position after the train has passed.
20. 4. A switch stand comprising means for operating the switch points to either set position, independent yieldable returning devices for permitting the switch points to be displaced by a train and for independently returning the switch points to set position, and means for holding said points in displaced position between the passage of successive wheels of a train but allowing either or both of said yieldable devices to return the switch points to set position after the train has passed.
25. 5. In a switch stand, means for operating the switch points to either set position, yieldable devices for permitting the switch points to be displaced from set position by a train, means for holding said points in displaced position between successive wheels of the train but allowing said devices to return the switch points to set position after the train has passed, and a signal indicating the position of the switch points at all times.
30. 6. In a switch stand, a casing, a star block journaled in said casing and having four rectangularly arranged rollers, a pair of horizontal, double acting spring assemblies on opposite sides of said star block, each spring assembly having a lug arranged between a pair of opposite rollers, a buffer comprising cylinder and piston members, one of said members being pivoted to said star block, the other of said members being pivoted to said casing, a locking block having an irregular part engaging an irregular part on said star block, a sleeve within said locking block, a spindle carrying a signal and disposed within said sleeve, a handle pivoted to said sleeve, said locking block having guide lugs for said handle, said handle and locking block having interengaging parts to lock the switch stand, a crank arm secured to said spindle, and a connecting rod pivoted to said crank arm and adapted to extend to the switch points, said locking block, sleeve and spindle having non-rotatable relation.
35. 7. In a switch stand, a casing, a star block journaled in said casing and having four rectangularly arranged rollers, a pair of horizontal, double acting spring assemblies on opposite sides of said star block, each spring assembly having a lug arranged between a pair of opposite rollers, a locking block having an irregular part engaging an irregular part on said star block, a sleeve within said locking block, a spindle carrying a signal and disposed within said sleeve, a handle pivoted to said sleeve, said locking block having guide lugs for said handle, a crank arm secured to said spindle, and a connecting rod pivoted to said crank arm and adapted to extend to the switch points, said locking block, sleeve and spindle having non-rotatable relation, and a device located in said casing for allowing said spring assemblies to be operated but retarding their return.
40. 8. In a switch stand, a casing, a star block journaled in said casing and having four, rectangularly arranged rollers, a pair of horizontal, double acting spring assemblies on opposite sides of said star block, each spring assembly having a lug arranged between a pair of opposite rollers, a buffer including cylinder and piston members, one of said members being pivoted to said star block, the other of said members being pivoted to said casing, a locking block having a non-circular end engaging a non-circular end on said star block, a non-circular sleeve within said locking block, a non-circular spindle carrying a signal and disposed within said sleeve, a handle pivoted to said sleeve and engaging said locking block, said locking block having guide lugs for said handle, said handle and locking block having interengaging parts to lock the switch stand, a crank arm secured to said spindle, a connecting rod pivoted to said crank arm and adapted to extend to the switch points, whereby said handle

may be locked with the switch points in either set position, and said switch points may be displaced from set position by a train against which the switch is set, in either set positions of the points, and said points will remain in displaced position between the passage of successive wheels of the train but will return to the set position after the train has passed, said signal indicating the position of the switch points at all times.

9. In a switch stand, a casing, a star block journaled in said casing and having four, rectangularly arranged rollers, a pair of horizontal, double acting spring assemblies on opposite sides of said star block, each spring assembly having a lug arranged between a pair of opposite rollers, a buffer comprising a cylinder and piston, said piston being pivoted to said star block, said cylinder being pivoted to said casing, a locking block having a squared end seating in a square seat in said star block, a squared sleeve within said locking block, a squared spindle carrying a signal and disposed within said squared sleeve, a bifurcated handle pivoted to said sleeve and straddling said locking block, said locking block having guide lugs for said handle, said handle and locking block having interengaging parts to lock the switch stand, a crank arm secured to said spindle, a connecting rod pivoted to said crank arm and adapted to extend to the switch points, whereby said handle may be locked with the switch points in either set position, and said switch points may be displaced from set position by a train against which the switch is set, in either set position of the points, and said points will remain in displaced position between the passage of successive wheels of the train but will return to the set position after the train has passed, said signal indicating the position of the switch points at all times.

10. In a switch stand, a switch stand casing, an operating member passing through said casing, a flag at the top of said operating member, a crank at the bottom of said operating member for connection to devices for operating the switch, a locking member in said casing, means for rotating said operating member to operate the switch and means for placing said locking member and operating member into and out of interlocking relation, yieldable devices in said casing between said casing and locking member, whereby the switch may be thrown by a train trailing the switch and the flag always moves with the switch.

In testimony whereof we have hereunto set our hands and seals.
